(57) **CLAIM**

I claim the ornamental design for a wrapping sheet, substantially as shown and described.

DESCRIPTION

FIG. 1 is a top view of a wrapping sheet in accordance with one embodiment of the present design;

FIG. 2 is a side view of the wrapping sheet in accordance with the design of FIG. 1;

FIG. 3 is a bottom view of the wrapping sheet in accordance with the design of FIG. 1;

FIG. 4 is a top perspective view of the wrapping sheet in accordance with the design of FIG. 1;

FIG. 5 is a top view of a wrapping sheet in accordance with another embodiment of the present design;

FIG. 6 is a bottom view of the wrapping sheet in accordance with the design of FIG. 5; and,

FIG. 7 is a perspective view of the wrapping sheet in accordance with the design of FIG. 5.

1 Claim, 4 Drawing Sheets
